[57] CLAIM

The ornamental design for a "seat", as shown and described.

DESCRIPTION

FIG. 1 is an enlarged perspective view of a seat, showing my new design in the form of a sofa;

FIG. 2 is a front view thereof;

FIG. 3 is a rear view thereof;

FIG. 4 is a left side view thereof, the right side being a mirror image thereof;

FIG. 5 is a view thereof, taken from above;

FIG. 6 is an enlarged perspective view of a seat, showing my new design in the form of an easy-chair;

FIG. 7 is a front view thereof;

FIG. 8 is a rear view thereof;

FIG. 9 is a left side view thereof, the right side being a mirror image thereof; and,

FIG. 10 is a view thereof, taken from above;
